BATHTUB SAFETY GRIP

Oscar Buhl and Henry V. Jacobus, Belleville, N. J.

Application May 31, 1934, Serial No. 728,403

3 Claims. (Cl. 4—185)

This invention relates to a bathtub safety grip and has for an object to provide a hand rail or safety grip which will increase safety for the bather entering or leaving the bathtub or while remaining in the bathtub and reducing the possibility of accidentally slipping or falling of the bather.

A further object of this invention is to provide an improved safety grip or hand rail which extends above the top edges of the bathtub and which may be made either as an integral part of the bathtub without however disturbing the fundamental original design or may be made as an attachment to be secured to existing bathtubs.

With the foregoing and other objects in view, as will hereinafter become apparent, this invention comprises the constructions, combinations, and arrangements of parts, hereinafter set forth, disclosed and shown on the accompanying drawing. In this drawing,

Figure 1 is a top plan view of the invention, Figure 2 is a side elevation of the same,

Figure 3 is an enlarged fragmentary view of the tub showing the hand grip integral with the same, and

Figure 4 is a view similar to Figure 3 showing the hand grip bolted on to the tub.

There is shown at 10 a bathtub which while of a built in type, may be of any conventional type. With bathtubs of this or any other type there is the ever present danger that the bather may slip and often seriously hurt himself either when entering or leaving the bathtub or while standing in the tub incidentally during the process of bathing. The bather usually instinctively grabs for the edge of the tub to steady himself and inasmuch as this edge is usually smooth porcelain and sometimes apt to be soapy and at least is wet, such action often serves merely to increase the danger of falling or slipping and thus increase the severity of the injury suffered by the bather. With this invention, however, such instinctive grabbing action at the edge of the bathtub results in affording a secure gripping means whereby the bather may quickly and easily steady himself and avoid injury. The gripping means constituting this invention includes a hand rail or grip 11, which rises above the top edge 12 of the bathtub 10, as shown in Figures 2 and 3.

This rail or grip 11 extends from adjacent one end 13 of the bathtub to the other end 14 of the tub, the rail 11 being supported by sloping portions 15 and 16 joining the top 12 of the bathtub and in the middle or in additional places if necessary and desirable by a brace 17. As will be

observed the bottom of the rail 11 is serrated as at 18. These serrations 18 provide grooves 19 therebetween so that the fingers of the bather may enter these grooves 19 and be prevented from slipping along the railing 11 by means of the serrations 18. A firm and secure grip is thereby provided. As will be observed, these serrations and grooves are present only on the bottom of the rail and not on the top of the rail, thereby making it possible to rest on the top of the rail in comfort and yet have a secure grip when desired.

It will be further noted that the rail or grip 11 is provided along the inner edge of each side of the bathtub 10 and likewise along the outer edge of the bathtub 10, thus affording quick and easy facility for either entering, leaving or standing in the bathtub. Furthermore, the rail 11 extends above the usual top 12 of the edge of the bathtub, thus allowing the bathtub to be of the usual size and hold the usual amount of water therein. These grips 11 afford an additional facility for steadyng one's self while reaching into the tub and cleaning the same preparatory to bathing.

In Figure 4 a hand rail or grip 20 is shown as being detachably secured by a bolt or set screw 21 to the top edge of a bathtub 22 of conventional construction. This hand rail or grip 20 is identical in construction with that shown at 11 being provided with the same serrations 18 and grooves 19 for the same purpose. A bathtub 30 is a somewhat expensive article and this attachable hand rail or grip 20 may be quickly and easily attached to any existing bathtub after making suitable inserted openings in the edge thereof to receive the screw or stud bolt 21.

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention.

Having thus set forth and disclosed the nature of this invention, what is claimed is:

1. In combination with a bathtub, a hand rail or grip secured to said bathtub along at least one edge thereof, said hand rail or grip extending above the top of the edge of the bathtub, said hand rail or grip having a smooth top surface and a serrated bottom surface affording finger gripping facilities, said hand rail or grip being an integral part of said tub.

2. For attachment in combination with a bathtub; a hand rail or grip adapted to be secured to

the bathtub along at least one edge thereof, said hand rail or grip extending above the top of the edge of the bathtub, said hand rail or grip being of a diameter to be easily grasped by the average hand, the surface of the upper side of said hand rail or grip being smooth and continuous, and the under surface of said hand rail or grip being divided by a plurality of serrations into a plurality of grooves thereby affording finger gripping facilities, said hand rail or grip being adapted to be secured to the top edge of the bathtub adjacent each end of the bathtub by gradually sloping portions.

3. In combination with a bathtub, a hand rail or grip secured to said bathtub along at least one edge thereof, said hand rail or grip extending

above the top of the edge of the bathtub, said hand rail or grip being of a diameter to be easily grasped by the average hand, the surface of the upper side of said hand rail or grip being smooth and continuous, and the under surface of said hand rail or grip being divided by a plurality of serrations into a plurality of grooves thereby affording finger gripping facilities, said hand rail or grip being secured to the top edge of the bathtub adjacent each end of the bathtub by gradually sloping portions, and brace means attaching said hand rail or grip to said top edge of said bathtub intermediate its ends.

OSCAR BUHL.
